UNITED STATES PATENT OFFICE

FARNUM F. DORSEY, OF ROCHESTER, NEW YORK, ASSIGNOR, BY MESNE ASSIGNMENTS, TO NORTH EAST APPLIANCE CORPORATION, OF ROCHESTER, NEW YORK, A CORPORATION OF NEW YORK

IGNITION-CIRCUIT CONTROLLER

Application filed September 12, 1929. Serial No. 392,194.

This invention relates to a circuit controller of the kind used in connection with the electric ignition apparatus of an internal combustion engine.

5 Any apparatus of the kind in question commonly comprises two contact members, one of which is supported in normally stationary but adjustable position, while the other is carried by a lever or other moving member actuated intermittently by a cam. For the purpose of adjusting the stationary contact, it is common to mount it upon a plate or block which is normally held fixed by a binding screw, but which may be slid 10 or swung, when the screw is loosened, to adjust the position of the stationary contact.

The adjusting movement just referred to is usually very slight, so that it is desirable to make some special provision for performing it with the necessary precision. The object of the present invention is to produce a circuit controller having such provision, but of simple and inexpensive construction. This has been accomplished 25 without the provision of any additional parts or mechanism, but merely by a particular formation of the parts which are essential to the circuit controller.

The invention is more particularly described in connection with the description of the embodiment thereof illustrated in the accompanying drawings, in which Fig. 1 is a plan view of the circuit controller; Fig. 2 is a side elevation, in section on the line 2—2 30 in Fig. 1, but with the cam omitted; and Fig. 3 is a detail plan view showing a modified form of the invention.

The invention is illustrated as embodied in a circuit controller comprising the usual base plate 5, a vertical pivot 6 fixed to the base plate, and a contact lever 7 pivoted on the stud and actuated by a rotary cam 8. The contact lever carries the usual contact 9, which cooperates with the stationary contact 10.

The stationary contact is fixed on a vertical lug 11, forming part of a sheet-metal arm 12 which lies flat against the upper surface of the base plate. The arm 12 is pivoted at one end, upon the stud 6, so that

it may have a swinging movement to adjust the position of the stationary contact. It is held in its adjustment position by means of a binding screw 13, which passes through a slot in the arm and is threaded into the base 55 plate in the usual manner.

The construction as so far described is not novel. The invention resides particularly in the formation of the arm and the base plate in such a manner as to provide, upon each, a recess of some sort, these recesses being so located that they may be engaged simultaneously by the end of a screw driver or similar tool. As shown in Fig. 1, the recess in the arm has the form of a notch 14, while the recess on the plate is provided by the space between two lugs 15 struck up from the metal of the plate. When the binding screw 13 is loosened by means of a screw driver, the end of the 60 screw driver may then be interposed between the lugs 15 and also partly in the notch 14, so that by turning the screw driver slightly the arm 12 may be swung in one direction or the other, through the slight distance 65 necessary for adjusting the contact 10. The screw 13 may then be tightened to lock the arm in its adjusted position.

The necessary recesses or abutment surfaces on the parts may be provided in various ways. Fig. 3 shows the arm as provided with a hole 16, lying partly above a similar hole 17 in the base plate. These holes have oppositely disposed narrow extremities adapted to engage, simultaneously, 70 opposite edges of the screw-driver blade, so that the arm may be adjusted by turning the screw driver the same as in the construction of Figs. 1 and 2.

The invention claimed is:

1. A circuit controller of the type comprising a moving contact member, a normally stationary contact member, a support for the stationary contact member, a base member on which said support is adjustably mounted, adjacent recesses formed in the support and base member to embrace simultaneously the opposite edges of a screw-driver or like tool, so that the support may be adjusted upon the base by turning the 80 85 90 95 100

tool, and means for fixing the support in adjusted position upon the base member.

2. A circuit controller of the type comprising a moving contact member, a normally stationary contact member, a base plate, a support, for the stationary contact member, in the form of an arm pivoted to and lying against the base plate and having a notch in its edge, a binding screw for clamping said arm in adjusted position against the base plate, two lugs on the base plate providing a recess adjacent to and in the plane of the notch in the arm, said notch and said recess being engageable simultaneously by a screw driver or like tool to adjust the arm by rotation of the tool.
